US00D934574S

(12) **United States Design Patent** (10) **Patent No.:** **US D934,574 S**
Underwood et al. (45) **Date of Patent:** **** Nov. 2, 2021**

(54) **FLAME RESISTANT FABRIC**

(71) Applicant: **Elevate Textiles, Inc.**, Greensboro, NC (US)
(72) Inventors: **Joey K. Underwood**, Greenville, SC (US); **Jacques A. Cantin**, Greenville, SC (US)

(73) Assignee: **International Textile Group, Inc.**, Greensboro, NC (US)

(**) Term: **15 Years**

(21) Appl. No.: **29/739,129**

(22) Filed: **Jun. 23, 2020**

Related U.S. Application Data

(63) Continuation-in-part of application No. 16/665,142, filed on Oct. 28, 2019, which is a continuation of application No. 15/331,950, filed on Oct. 24, 2016, now abandoned.

(57) CLAIM

The ornamental design for a flame resistant fabric, as shown and described.

DESCRIPTION

FIG. 1 is a top view of a flame resistant fabric according to the present design; and,

FIG. 2 is a top view of an enlarged detail view of area 2 circumscribed within FIG. 1.

The broken lines surrounding FIGS. 1 and 2 depict the boundaries of the claim and form no part thereof. The broken lines within FIG. 1 and surrounding FIG. 2 denote the boundaries of the detail area and form no part of the claimed design.

1 Claim, 2 Drawing Sheets
